UNITED STATES PATENT OFFICE

GEORGE H. HAMILTON, OF GRAND RAPIDS, MICHIGAN, ASSIGNOR TO AMERICAN SEATING COMPANY, OF GRAND RAPIDS, MICHIGAN, A CORPORATION OF NEW JERSEY

CHAIR-SEAT END CONSTRUCTION

Application filed April 23, 1928. Serial No. 272,000.

This invention relates to chair seat end constructions particularly useful for theatres and the like.

The main objects of this invention are to 5 provide improved means for the light cover shield to a seat end; to provide a shield attaching means which requires but one bolt; and to provide an improved construction of seat end which permits the grounding of the 10 electric light conduit in order to conform to the rules governing electric installations in large cities.

An illustrative embodiment of this invention is shown in the accompanying drawings, 15 in which:

Fig. 1 is a view in perspective of a theatre chair embodying this invention.

Fig. 2 is a fragmentary view in perspective of the inner side of the seat end shown in 20 Fig. 1.

Fig. 3 is a view in medial vertical section of the same.

Heretofore in the construction of theatre seat ends, the shield for the electric light has 25 ordinarily been secured to the seat end by a pair of bolts or screws positioned one at each side of the shield. By such construction the shield depended solely upon the bolts for being held in position and when it was necessary to remove the shield for servicing the light, the operation was more or less of an 30 awkward one.

In my improved construction, the shield is embraced at its opposite sides by shoulders 35 and at its lower end by a lug which also acts to some extent as a hinge. One bolt or screw only is provided and is positioned at the top end of the shield so that the servicing of the light is a very simple and readily accomplished operation.

In the construction shown in the drawings, 45 a theatre seat 1 is provided with a cast iron end standard 2 having a depressed center panel portion 3, which is bounded along its vertical edges by protruding shoulders 4 and 5. The upper end of the panel portion 3 is further depressed to form a recess 6 for receiving and housing an electric light 7 mounted in a vertical position on a horizontally disposed bracket 8.

A portion of the recess wall is abruptly depressed to provide a horizontal wall 9 which has a vertically disposed opening therein that is threaded to receive an electric wire conduit fitting 10. In the construction shown, this 55 fitting is shown as being the type to receive a flexible armored cable 11, but in case pipe is used, a short nipple thereof may be threaded into this opening. In either instance the construction is such as to provide a ground 60 connection for the wire conduit.

A cover shield plate 12 is provided for fitting against the face of the panel portion, over the recess 6, the vertical sides thereof being embraced by the shoulders 4 and 5. 65

Means are provided for detachably securing the shield 12 to the seat end, and comprise an inwardly extending lug 13 integrally formed at the lower extremity of the shield, which is adapted to extend through an aperture 14 in the panel portion 3, located adjacent the lower end of the recess 6. The aperture 14 is of substantially the same size and shape as the cross sectional size of the lug 13, and the inner end of the lug has a depending toe 15 thereon which bears against the inner wall of the panel 3. 70

The lug 13 and toe 15 cooperate with a bolt 16 which passes through the extreme upper end of the shield 12, at the medial point 75 thereof, and through the seat end, to hold the shield securely in place between the shoulders 4 and 5.

When it is desired to remove the shield 12 for servicing the light 7, the bolt 16 is first removed and the upper end of the shield swung outwardly and downwardly in an arc until the toe 15 is in substantially axial alignment with the aperture 14, at which time the lug and toe are withdrawn. 80

By reversing the foregoing operations, the assembly is accomplished. It will be seen that by this construction, the weight of the shield does not rest upon bolts or screws but is carried by the lug 13, and sidewise displacement of the shield is prevented by the shoulders 4 and 5. 85

Although but one specific embodiment of this invention has been herein shown and described, it will be understood that numerous 100

details of the construction shown may be altered or omitted without departing from the spirit of this invention as defined by the following claims.

5 I claim:

1. In a seat of the character described: a seat end having a middle portion and side portions projecting outwardly therefrom, said middle portion having a keeper orifice 10 and a depression housing an electric lamp above the keeper orifice; a shield for the lamp detachably applied to the face of the middle portion in an assembled position wherein its edges engage said side portions, the shield 15 having at its lower end a lug adapted to be thrust into the keeper orifice in a horizontal assembling position of the shield and to engage said middle portion in the assembled raised position of the shield, the shield having at its upper end releasable means for securing the same to said middle portion in assembled position.
2. In a seat of the character described: a seat end having a keeper orifice and a depression housing an electric lamp above the 25 said orifice; a shield for the lamp having portions adjacent its opposite edges contacting the face of the seat adjacent the depression and at its lower end a lug adapted to be thrust 30 into the keeper orifice in a horizontal assembling position of the shield and to engage said middle portion in the assembled raised position of the shield, the shield having an upper end portion received into the depression in 35 such assembled position; threaded means for securing said upper end portion in the depression.
3. In a seat of the character described: a metallic cast seat end having a depression 40 comprising a main portion housing an electric lamp and a laterally extending portion having a horizontal side wall provided with an opening therethrough for receiving a vertically disposed electric wire conduit in electrically grounded relation to the seat end. 45

In testimony whereof I have hereunto set my hand at Grand Rapids, Michigan, this 21st day of April, 1928.

GEORGE H. HAMILTON.
